GOLF MARKER

Filed Oct. 25, 1928

UNITED STATES PATENT OFFICE

SAMUEL P. SEARS, OF BOSTON, AND JEREMIAH A. SULLIVAN, OF NEWTON CENTER,
MASSACHUSETTS

GOLF MARKER

Application filed October 25, 1928. Serial No. 315,075.

This invention relates to markers for use on golf links for indicating to the golfer at a tee the location of the cup in the distant green and the precise distance from the tee to the cup.

An object of the invention is to provide a marker of unitary construction which will convey to the golfer all the information necessary to enable him to calculate the direction and distance of his drive, whether or not the green is visible from the tee. The indications of the marker, moreover, are of such character as to be visible and conspicuous and may be adjusted in accordance with variations in the location of the tee or of the cup in the distant green. It is the practice to change the location of the cup in the green frequently in order to avoid wearing bare the turf, and in a large green a wide variation in location is possible which affects not only the length of the hole but the direction in which the green can be most favorably approached. It is also customary to change the location of the tee occasionally or to provide a second tee for women players, located somewhat nearer to the green than the tee used by men players. These conditions introduce an element of uncertainty which the present invention aims to eliminate.

In one aspect, the invention consists in a golf marker which includes a green chart having adjustable means for designating thereon the position of the cup in the distant green. As herein shown, the green chart is laid out in defined areas and means is provided for selectively indicating on the chart the area corresponding to that in which the cup in the distant green is then located. If, for example, the cup should be located toward the left side of the green and near the center from back to front, the indicating means in the chart will be arranged to designate the left-hand central area, while if the cup should be located toward the rear right-

hand corner of the green the location of the indicating means in the chart is changed to the corresponding area. With this information available, the golfer may calculate his drive so as to approach the green from the most favorable side or, if possible, to reach the green in the area wherein the cup is located. The increasing distance of drives and the accuracy of direction now being developed in the game render the information thus conveyed to the golfer of material assistance.

The invention also contemplates the provision of a yardage register for indicating the distance of the marker, or of the tee whereat it is located, from the green and from the particular area in which the cup is located and as indicated upon the green chart. As herein shown, the registering device comprises a series of numbered drums which may be rotated to display a figure indicating the yardage in question. The drums are freely rotatable on a spindle contained in the casing of the marker and are provided with locking mechanism for holding them in adjusted position. As herein shown, each drum is provided with a rib adapted to be engaged by a clamping screw set in a frame member carried by the spindle upon which the drum is turned. The whole assembly is arranged as a unit which may be detached and removed from the casing, if desired, and which construction is convenient in assembling the elements of the marker.

These and other features of the invention will be best understood and appreciated from the following description of a preferred embodiment thereof, selected for purposes of illustration and shown in the accompanying drawings, in which

Fig. 1 is a view in perspective of the marker;

Fig. 2 is a vertical sectional view; and

Fig. 3 is a transverse sectional view on the line 3-3 of Fig. 2.

The body of the marker comprises a sheet

metal casing 10 having an inclined front wall 12 and a leg 16 at each corner adapted to be forced into the turf on a tee and thus anchor the marker in position. The inclined front face 12 carries an arrow indicating the general direction of the distant green and designation indicating the number of the hole, and a window 14 framing a display aperture for the yardage register. This is covered by 10 a pane of glass so that the body of the marker comprises a complete weatherproof casing.

Within the casing and on opposite sides thereof are provided a pair of lugs 30 to which is detachably secured a transverse 15 spindle 32. Journaled to rotate freely upon the spindle 32 are concentric drums 20, 22 and 24 each carrying upon its periphery a series of figures from 0 to 9. At one end each drum is provided with a stiff flange 25. A stationary 20 stirrup-shaped frame 34 is pinned to the spindle 32 and extends across the bottom of the drums where it is provided with clamping screws 36, one disposed opposite to the flange of each drum and serving to release 25 or to lock the individual drums in any position of adjustment. The spindle 32 is so located that the peripheries of the three drums are brought into the display aperture of the window 14 and into close proximity to the 30 glass thereof so that the figures carried by the drums are displayed conspicuously. It will be apparent that the drums with their locking mechanism may be assembled on the spindle 32 as a unit and then mounted within 35 the casing.

The upper surface of the marker is flat and has secured thereto a green chart comprising a plate 40 laid out by lines 42 in defined areas or squares which are numbered 40 serially for purposes of identification. In each square is provided a threaded socket 44 and a marker simulating a flag and having a threaded stem may be inserted in any one of the sockets 44 which appropriately 45 designates the corresponding area of the distant green in which the cup is at the time located.

It will be apparent that the golfer coming to the tee and glancing at the marker above 50 described may orient the green chart with the distant green and by observing the area in which the flag 46 is inserted ascertain at once the location of the cup in the distant green. Also, the exact number of yards 55 from the tee to the cup is conspicuously displayed in the window 14. With this information available, the golfer requires only the requisite skill in driving to place his ball in the most favorable position for the succeeding 60 shot.

It is believed that heretofore a distance 65 register has never been combined with visual means for indicating the location of the cup which constitutes the other terminus of the measured line. It will be apparent that we

locate our marker at one end of a measured line and the position of the cup, which constitutes the other end of the measured line, is visually indicated by the marker. Variations in the position of the cup are indicated by appropriately changing the position of the flag 46 in the green chart and the corresponding variation in the measured line from the marker to the cup is indicated by correspondingly adjusting the register. This combination is believed to be broadly new. 75 Further, it is believed that heretofore no device has ever been available for visually indicating at the tee the position of the cup in the distant green, whether associated or not 80 with a distance register.

Many modifications and changes in detail will readily occur to those skilled in the art without departing from the spirit and scope of our invention, but having set forth the objects and nature of our invention, and having shown and described a construction embodying the features thereof, what we claim 85 as new and desire to secure by Letters Patent is:

1. A portable marker for golf comprising a support bearing a chart of the green in miniature, said support having means for anchoring the marker at the tee so as to orient the green chart with the actual distant green, and said green chart being arbitrarily divided symmetrically into a plurality of like areas indicating a corresponding mythical division of the green each such area having means for holding a signal device to indicate the divisional location of the cup in the green at any particular time, and a single signal device for selective association with the holding means of any area of the green chart. 90

2. A portable marker for golf comprising a support bearing a chart of the green in miniature, said support having means for anchoring the marker at the tee so as to orient the green chart with the actual distant green, and said green chart being arbitrarily divided symmetrically into a plurality of like areas indicating a corresponding mythical division of the green each such area having a hole therein, and a signal having a part fashioned to fit any hole and to be selectively fitted in the hole of the green chart area corresponding to the area of the green in which the cup may be located. 105

3. A portable golf marker, to be positioned at selective driving areas of a tee varying in distance from a green, having a numerical yardage register and a green chart divided into areas corresponding to selective placements of the cup in the green said chart being provided with an adjustable indicator to designate the area of the green in which the cup may be located at any time, means for setting the numerals of the yardage register to satisfy the two variables of selective 110

locations of the driving area at the tee and the cup placement in the green as they may exist at any time and for securing said numerals against displacement after the correct yardage has been determined, and means for anchoring the marker in the turf at the selected driving area of the tee.

In testimony whereof we affix our signatures.

10 SAMUEL P. SEARS.
